UNITED STATES PATENT OFFICE.

OSCAR E. BRANDT, OF BROOKLYN, NEW YORK, ASSIGNOR TO THE STANLEY WORKS, OF NEW BRITAIN, CONNECTICUT, A CORPORATION OF CONNECTICUT.

DESIGN FOR A HINGE-LEAF.

No. 39,364.

Specification for Design.

Patented June 16, 1908.

Application filed March 11, 1908. Serial No. 420,502. Term of patent 14 years.

To all whom it may concern:

Be it known that I, OSCAR E. BRANDT, a citizen of the United States, residing at Brooklyn, in the county of Kings and State of New York, have invented a new, original, and ornamental Design for a Hinge-Leaf, of which the following is a specification, reference being had to the accompanying drawing, forming part thereof.

The figure is a plan view of a hinge leaf showing my design.

I claim:

The ornamental design for a hinge leaf, as shown.

OSCAR E. BRANDT.
